UNITED STATES PATENT OFFICE.

CHARLES THOMAS BROCK SANGSTER, OF BIRMINGHAM, ENGLAND.

DESIGN FOR A BICYCLE-FRAME.

SPECIFICATION forming part of Design No. 34,254, dated March 19, 1901.

Application filed February 21, 1901. Serial No. 48,378. Term of patent 3½ years.

To all whom it may concern:

Be it known that I, CHARLES THOMAS BROCK SANGSTER, general manager of The Cycle Components Manufacturing Company, Limited, a subject of the King of Great Britain, residing at Bournbrook, Birmingham, England, have invented and produced a new and original Design for a Bicycle-Frame, of which the following is a specification.

10 The drawing represents a perspective view of my new and original design for a bicycle-frame.

The leading or material feature of my design consists in the arrangement or disposition of a stay member a , running diagonally throughout the whole length of the machine. The fore part a' consists of a single member running from the top of the head c to about the center of the seat-tube d , while the rear portion a^2 , which is forked or double-sided, is continued rearward from the said seat-tube and terminates at the junction of the chain-

stays e and backstays f . A second diagonal tube b runs from the bottom of the head diagonally upward to the top of the seat-tube d and intersects the fore part a' of the member a at a^3 , where the respective tubes are connected by a four-way junction-lug. The frame is completed by the usual front diagonal tube h , running from the head to the 30 crank-axle bearing-bracket i .

Having described my invention, what I claim as new, and desire to secure by Letters Patent, is—

The design for a bicycle-frame as herein 35 described and shown.

In testimony whereof I have hereunto set my hand in presence of two subscribing witnesses.

CHARLES THOMAS BROCK SANGSTER.
